UNITED STATES PATENT OFFICE.

EDWARD MEAD JOHNSON AND ERNEST J. COLLINGS, OF JERSEY CITY, NEW JERSEY,
ASSIGNORS TO MEAD JOHNSON & CO., OF JERSEY CITY, NEW JERSEY, A CORPO-
RATION OF NEW JERSEY.

APPARATUS FOR DRYING LIQUIDS.

1,200,117.

Specification of Letters Patent.

Patented Oct. 3, 1916.

Original application filed March 8, 1915, Serial No. 12,858. Divided and this application filed October 9, 1915. Serial No. 54,990.

To all whom it may concern:

Be it known that we, EDWARD MEAD JOHNSON and ERNEST J. COLLINGS, citizens of the United States, residing at Jersey City, in Hudson county, in the State of New Jersey, have invented certain new and useful Improvements in Apparatus for Drying Liquids, of which the following is a specification.

10 This invention relates to apparatus for drying liquids of the type in which the liquid is dried while thinly spread upon a surface, and is a division of our application Serial Number 12,858, filed March 8th, 1915.

15 The apparatus is particularly applicable to the drying of liquids containing solid matter in suspension or solution.

An object of the invention is to provide an apparatus adapted to dry highly adhesive 20 solutions, especially those which are extremely adhesive when heated.

Furthermore, our new apparatus is adapted to the drying of mixtures composed of 25 solutions of different degrees of adhesive- ness and to regulate the proportion of the different solutions so as to obtain the desired constitution of the dried product.

Our new drying apparatus consists fundamentally of means for spreading a film of a 30 solution over the surface upon which the drying is to take place and means for applying upon this film a film of another solution.

An important use of our new apparatus 35 is in the drying of syrups. Malt sugar syrup, for example, consists principally of two substances, dextrin and maltose in solution. The maltose is extremely adhesive when heated, while the dextrin is much less so. In former drying apparatuses it has been customary to dry the malt sugar syrup by spreading a film of the mixture of dextrin and maltose in solution over a heated surface. This results in bringing a part 40 of the heated maltose in contact with the heated surface, and its extreme adhesiveness makes it difficult to remove from the heated surface after drying. It is, as a practical matter, impossible to remove the dried film 45 when the ratio of the maltose to the dextrin in the solution is greater than 55:45. By means of our new apparatus a solution con-

taining either pure dextrin or a high percentage of dextrin and a solution containing a high percentage of maltose are spread 55 upon the heated surface separately and successively. A film of the high dextrin solution is first applied and over this a film of the high maltose solution. The film high in dextrin prevents the maltose from coming 60 in contact with the heated surface and in consequence the two films may easily be scraped off when dried.

In order that our invention may be clearly understood, we shall proceed to describe the 65 particular embodiment of it which is illustrated in the accompanying drawing. It should be clearly understood, however, that our invention is by no means limited to the 70 particular apparatus illustrated and described.

In the accompanying drawing, Figure 1 is a cross-sectional elevation of a device embodying our invention. Fig. 2 is a fragmentary section of a modified form of the 75 device.

In the form illustrated the drying apparatus is inclosed in an air-tight casing 1, to which is connected an exhaust pipe 13. This makes it possible to conduct the dry- 80 ing in a vacuum. The use of a vacuum is, however, not essential to our invention and whether or not it is to be used in connection with our invention may be determined by practical considerations as to the cost and 85 rapidity of drying required and particularly by the nature of the solution to be dried.

The drying roller 2 is supported upon a horizontal axle, one end of which is hollow 90 to permit the introduction of steam into the interior of the roller. Any convenient form of mechanism, not shown, is provided to rotate the roller in an anti-clockwise direction. This mechanism is such that the speed of 95 rotation may be varied. Below the roller 2 are the rollers 3 and 4. These rollers are supported upon horizontal axles and are preferably capable of being steam heated like roller 2. A very small clearance is 100 allowed between these rollers and roller 2, that between roller 3 and roller 2 being equal to the thickness of the film of the liquid to be dried, and that between roller 4

and roller 2 being equal to the thickness of two films of solution. Rollers 3 and 4 are provided with mechanism (not shown) by which they can be rotated in clockwise direction. Surrounding the lower portions of the rollers 3 and 4 are the troughs 5 and 6, in which are placed the solutions to be dried. Inlet pipes 7 and 8 are provided to admit the solutions to the troughs 5 and 6, respectively. The troughs are also provided with outlet pipes 9 and 10, which are used when the troughs are washed out. A knife 11 is provided to scrape the dried films from the roller 2. From the knife the dried product descends into the receptacle 12.

The operation of the apparatus illustrated in Fig. 1 is as follows:—Steam is admitted to the roller 2, and preferably to rollers 3 and 4 also, to heat them. The solutions to be dried are introduced into the troughs 5 and 6 through pipes 7 and 8, the more adhesive solution being placed in trough 6. If, for example, the solution to be dried is malt sugar syrup, the solution of dextrin or 25 high in dextrin is admitted to trough 5, while the high maltose solution is run into trough 6. The rollers are then rotated, roller 2 in an anti-clockwise direction and rollers 3 and 4 in a clockwise direction. The 30 peripheral velocity of roller 2 is preferably slightly greater than that of rollers 3 and 4, so that the film of solution carried up upon rollers 3 and 4 is drawn upon the surface of roller 2 as it passes over them. By this arrangement, a film of the solution contained in trough 5 is first applied to roller 2 and then a film of the more adhesive solution in trough 6 is applied outside of this film. The 35 film of the more adhesive solution is thus kept out of contact with roller 2 and does not, therefore, stick to the roller when dried. The two films are scraped from the roller 2 by the knife 11 and fall into the receptacle 12 in the form of a dry powder.

In the modification of the apparatus shown in Fig. 2, rollers 3 and 4 are placed at such a distance from the roller 2 that the film of solution upon them is not brought directly in contact with the roller 2. In this 50 modification, the rollers 3 and 4 are rotated at a sufficiently high velocity to throw the solution upon them against the roller 2 by centrifugal force.

The axles of the rollers 3 and 4 may be 55 so supported as to be vertically adjustable. In this case these rollers may be so adjusted as to operate either as shown in Fig. 1 or as in Fig. 2.

The apparatus may be used to dry a single highly adhesive liquid which could not 60 be dried on a heated roller by the ordinary method. In this case the adhesive liquid is placed in the trough 6 and oil or other suitable liquid of low adhesiveness is placed in 65 the trough 5 to form a film which shall pre-

vent the adhesive liquid from adhering to the roller 2.

An important use of the apparatus is to obtain a dry product which is composed of a mixture of the solid constituents of solutions of different adhesiveness. In this case as already explained, the more adhesive solution is placed in the trough 6 and is thus prevented from coming in contact with the roller. Furthermore, the apparatus permits 70 of the regulation of the proportion of the constituents of the different solutions which appear in the dried product. This is done by regulating the thickness of the films of the various solutions applied to the roller 2. 75 Regulation may be accomplished in various ways. Thus, a thicker film of one solution may be produced by maintaining that solution at a higher level in its trough by admitting the solution to the trough more rapidly. A thicker film of the solution may also be applied by rotating the roller which is applying the film more rapidly. This method is peculiarly applicable when the film is applied centrifugally, as shown in 80 Fig. 2.

It is obvious that many modifications may be made in the apparatus described without departing from our invention. Thus, the drying roller may itself dip into a trough 95 containing one of the liquids, while the other liquid is applied by a roller similar to roller 3. Or one or both of the solutions may be applied by suitable spraying devices or by means of any other mechanism for applying films to a roller. If it is desired to obtain a mixture of the solid constituents of more than two liquids, additional rollers and troughs similar to rollers 3 and 4 and troughs 5 and 6 may be used, or a number of spraying devices or other means for applying films 100 may be used equal to the number of liquids to be dried. Thus, any number of liquids may be dried and the solid constituents mixed in any desired proportion.

What we claim is:

1. A drying apparatus comprising a drying roller and a plurality of rollers arranged to apply a plurality of films of liquid to said drying roller.

2. A drying apparatus comprising a drying roller and a plurality of rollers arranged to throw a plurality of films of liquid upon said drying roller by centrifugal force.

3. A drying apparatus comprising a heated drying roller, a plurality of troughs containing liquids, and a plurality of rollers in said troughs arranged to apply films of the liquids contained therein to said drying roller.

4. A drying apparatus comprising a drying roller, and means spaced apart around the periphery of said roller for applying films of liquid to said roller at spaced points along its periphery.

5. A drying apparatus comprising a drying roller, means for applying a film of liquid to said roller, and means spaced apart from said first mentioned means for applying a film of liquid upon said first mentioned film at a point spaced apart from the point at which said first mentioned film is applied to the roller.
6. A drying apparatus comprising a moving drying surface and spaced means for

applying films of liquids at spaced points along said surface.

In testimony whereof, we have hereunto set our hands this 28 day of Sept., 1915.

EDWARD MEAD JOHNSON.

ERNEST J. COLLINGS.
